H. O'B. HARDING,
CONVEYING AND ELEVATING APPARATUS,
APPLICATION FILED DEC. 21, 1918.

1,352,262.

Patented Sept. 7, 1920.

Inventor:
Henry O'B. Harding.
By Whitley and Ruckman
His Attorneys.

UNITED STATES PATENT OFFICE.

HENRY O'B. HARDING, OF MINNEAPOLIS, MINNESOTA.

CONVEYING AND ELEVATING APPARATUS.

1,352,262.

Specification of Letters Patent. Patented Sept. 7, 1920.

Application filed December 21, 1918. Serial No. 267,791.

To all whom it may concern:

Be it known that I, HENRY O'B. HARDING, a citizen of the United States, residing at Minneapolis, in the county of Hennepin 5 and State of Minnesota, have invented certain new and useful Improvements in Conveying and Elevating Apparatus, of which the following is a specification.

My invention relates to a conveying and 10 elevating apparatus and particularly to an apparatus of this kind intended for use in mills for conveying and elevating filled sacks of flour. An object of my invention is to provide an apparatus which will contain 15 vey filled sacks in upright position underneath a device for closing the upper ends thereof and deliver the closed sacks in recumbent position to an elevating apparatus so that the sacks will lie lengthwise upon 20 lifting fingers secured to the elevating apparatus.

The full objects and advantages of my invention will appear in connection with the 25 detailed description thereof and the inventive idea embodied in my construction will be particularly pointed out in the claims.

Referring to the accompanying drawings, which illustrate the application of my invention in one form,—

30 Figure 1 is a top plan view. Fig. 2 is a view in vertical section on the line 2—2 of Fig. 1. Fig. 3 is a front view. Fig. 4 is an enlarged detail view of the lower portion of the construction shown in Fig. 3.

35 In the construction shown in the drawings, 10 designates a sewing machine or other closing device underneath which passes a belt 12 traveling the direction of the arrow *a* and positioned to carry filled 40 sacks with their open tops underneath the device 10 by which they are closed. A short endless belt 14 is positioned adjacent the delivery end of the belt 12 with its direction of travel at right angles to the direction 45 of travel of the belt 12. The upper stretch of the belt 14 travels in the direction of the arrow *b* and is positioned at a somewhat lower level than the belt 12. The belt 14 passes around end rollers 16 and 18 and the 50 upper stretch is supported by idlers 20. A driving pulley 17 is secured to the shaft of one of the end rollers. Adjacent the delivery end of the belt 14 is a comb 22 attached to the frame 24. An endless elevat-

55 ing belt 26 passes over an upper roller 28 and a lower roller 30, these rollers being

mounted in the side members 32 and 34. A driving pulley 29 is secured to the shaft of the upper roller. Attached to the belt 26 at regular intervals are sack-elevating 60 members 36 consisting of fingers adapted to pass between the teeth of the comb 22. Adjacent the upper or delivery end of the belt 26 is an inclined plate 38 having teeth 40 between which the fingers of the lifting 65 members 36 are adapted to pass. Passing underneath the lower end of this plate is the receiving end of a traveling belt 42.

The operation and advantages of my invention will be readily understood from 70 the foregoing description. Filled sacks are placed in upright position upon the belt 12 which carries them underneath the device 10 which closes the upper ends thereof. The closed sacks when they reach the 75 delivery end of the belt 12 are tipped over into recumbent position upon the belt 14 which carries them to the elevating apparatus 26 for engagement by the lifting fingers thereof so that the sacks lie lengthwise 80 upon these fingers. The sacks when in this position are readily taken up by the elevating apparatus and are also readily discharged from the elevating apparatus at the upper end thereof.

85 I claim:

1. A conveying and elevating apparatus comprising means for carrying filled sacks underneath a device for closing the upper ends thereof, means for receiving the 90 closed sacks and carrying them in a direction at an angle to the direction in which sacks are carried by said first-mentioned means, and means for elevating the closed sacks as they are delivered thereto 95 by said second-mentioned means.

2. A conveying and elevating apparatus comprising a belt for carrying filled sacks underneath a device for closing the upper ends thereof, an endless belt adjacent the 100 delivery end of said first-mentioned belt, said belts being mounted to travel in directions at right angles to each other, and an elevating belt having its lower end positioned adjacent the delivery end of said end- 105 less belt.

3. A conveying and elevating apparatus comprising a belt for carrying filled sacks underneath a device for closing the upper ends thereof, an endless belt having its 110 upper stretch adjacent and lower than the delivery end of said first-mentioned belt,

said belts being mounted to travel in directions at right angles to each other, and an elevating belt having its lower end positioned adjacent and lower than the delivery 5 end of said endless belt.

4. A conveying and elevating apparatus comprising a belt for carrying filled sacks underneath a device for closing the upper ends thereof, an endless belt adjacent the 10 delivery end of said first-mentioned belt, said belts being mounted to travel in directions at right angles to each other, a comb mounted adjacent the delivery end of said endless belt, an elevating belt having its 15 lower end positioned beneath said comb, and a plurality of lifting members attached to said elevating belt, said members consisting of fingers adapted to pass between the teeth of said comb.

20 5. A conveying and elevating apparatus comprising a belt for carrying filled sacks underneath a device for closing the upper ends thereof, an endless belt adjacent the delivery end of said first-mentioned belt, 25 said belts being mounted to travel in directions at right angles to each other, a comb mounted adjacent the delivery end of said endless belt, an elevating belt having its lower end positioned beneath said comb, a 30 plurality of elevating members attached to said elevating belt, said members consisting of fingers adapted to pass between the teeth of said comb, and an inclined plate adjacent the upper end of said elevating belt, said

plate having teeth between which said fingers are adapted to pass. 35

6. A conveying and elevating apparatus comprising a belt for carrying filled sacks underneath a device for closing the upper ends thereof, an endless belt having its upper stretch adjacent and lower than the delivery 40 end of said first-mentioned belt, said belts being mounted to travel in directions at right angles to each other, a comb mounted adjacent the delivery end of said endless belt, an elevating belt having its lower end underneath said comb, and a plurality of 45 lifting members attached to said belt, said members consisting of fingers adapted to pass between the teeth of said comb. 50

7. A conveying and elevating apparatus comprising a belt for carrying filled sacks underneath a device for closing the upper ends thereof, an endless belt mounted to travel at right angles to said first-mentioned belt and having its upper stretch adjacent and lower than the delivery end of said first-mentioned belt whereby said closed sacks are tipped into recumbent position 55 upon said endless belt, an elevating belt for receiving sacks at its lower end from the delivery end of said endless belt, and a traveling belt for receiving sacks from the upper end of said elevating belt. 50

In testimony whereof I hereunto affix my 65 signature.

HENRY O'B. HARDING.
